SWITCH OPERATING MECHANISM

Carl H. Bissell, Syracuse, N. Y., assignor to
 Crouse-Hinds Company, Syracuse, N. Y., a corporation of New York

Application January 25, 1940, Serial No. 315,568

5 Claims. (Cl. 200—153)

This invention relates to mechanism for operating electrical switches.

The invention has as an object a particularly simple and efficient mechanism which may be conveniently secured to or mounted upon a conventional switch box or housing, and which embodies a unitary structure including means to effect operation of the switch by means of foot pedals.

The invention has as a further object a pedal operated switch actuating mechanism formed as an integral part of a closure for the switch housing and embodying the provision of means whereby the switch may be actuated either manually, or by the foot pedals, or both manually and by the foot pedals. The structure is so arranged that the mechanism may be originally installed for either manual or foot operation, and can be conveniently changed on the job to include both methods of operation, or changed from one method of operation to the other.

The invention consists in the novel features and in the combinations and constructions hereinafter set forth and claimed.

In describing this invention, reference is had to the accompanying drawings in which like characters designate corresponding parts in all the views.

Figure 1 is a front elevational view of a switch actuating mechanism embodying my invention.

Figure 2 is a view, similar to Figure 1, with the cover plate removed and the pedal structure shown in section.

Figure 3 is a vertical sectional view, partly in elevation, taken on line 3—3, Figure 2, illustrating the mechanism mounted on the switch housing.

Figure 4 is a fragmentary sectional view taken on line 4—4, Figure 2.

The switch housing 10 may be of any suitable type or construction. It is here shown in the nature of a box of general rectangular form provided with one or more hubs 11 having conduit receiving apertures, whereby the housing may be properly connected in a conduit system. The top or face side of the housing is formed with a substantial opening. A switch 12, here illustrated as of the conventional toggle type, is mounted in the housing in the usual manner with the operating handle 13 extending outwardly toward or through the opening of the housing.

The actuating mechanism includes a closure member 14 for the opening in the housing. Preferably, the closure member is also of box formation having a bottom wall 15 and end walls 16.

The bottom wall 15 overlies the marginal surface about the opening of the housing and is formed with a raised portion 17 extending transversely across the central portion of the closure member.

5 The closure member is detachably mounted upon and secured to the housing by a stud 18 extending through apertures formed in the bottom wall 15 adjacent each corner of the closure member and threading into the housing. The studs 18 extend outwardly and terminate adjacent the outer edge of the wall 16, and are formed with threaded apertures to receive screws 19 to secure an outer cover 20 to the closure member.

A rock shaft 21 is journaled in the raised portion 17 adjacent one side of the closure member, see Figure 2, and is provided at its inner end with a bifurcated member 23 arranged to engage the switch handle 13 and to actuate the same into on and off positions upon oscillation of the shaft.

10 An angle lever 24 is secured to the outer end of the shaft 21, as by set screw 25, and is provided with an elongated arm 26 extending through a slot 27 formed in one of the side walls 16 of the closure member and serves as a manual by which the switch may be actuated by hand. The lever 24 is provided with a shorter arm 28 to which one end of a link 29 is pivotally connected, and the opposite end pivotally connected to a boss 30

15 extending laterally from a lever 31 journaled intermediate its ends on a stud 32 secured to the raised portion 17 of the bottom wall of the closure member.

An angle lever 24 is secured to the outer end of the shaft 21, as by set screw 25, and is provided with an elongated arm 26 extending through a slot 27 formed in one of the side walls 16 of the closure member and serves as a manual by which the switch may be actuated by hand. The lever 24 is provided with a shorter arm 28 to which one end of a link 29 is pivotally connected, and the opposite end pivotally connected to a boss 30 extending laterally from a lever 31 journaled intermediate its ends on a stud 32 secured to the raised portion 17 of the bottom wall of the closure member.

20 One of the walls 16 is provided with a hub portion 35 threaded to receive a tubular guide member 36 which may be secured in place as by a set screw 37. The tubular guide member 36 extends outwardly from the closure member, or depends therefrom, parallel to the surface of the wall 38 in which the body 10 is mounted, to a point where the pedals carried by the guide member may be conveniently operated by foot.

The mechanism is here shown as being provided with two foot pedals 40 slidably mounted in the lower end of the tubular member 36. The pedal members 40 are formed with laterally extending projections 41 extending radially through axially extending slots 42 formed in the lower end of the guide member 36. Each of the pedal members 40 is operatively connected with the respective ends of the lever 31 as by wires 43. The lower ends of the pedal members are formed with a recess to slidably receive a plug 45, and the lower end of each of the wires 43 extends through an aperture formed in the upper por-

25

tion of each pedal member and are secured to the plug members 45. A helical compression spring 46 is interposed between each plug 45 and the pedal member. This arrangement is to provide a yielding connection between the wires 43 and the pedal members 40. A cap 47 is secured to the lower end of the guide member 36. Preferably, the pedal members 40 are separated by a partition 48, the lower end of which is arranged in a plug 49 mounted in the cap 47, as by screw 50.

The ends of the lever 31 are bifurcated and provided with an aperture to rotatably receive a pin 51. Each of the pins 51 is provided with a transversely extending aperture located centrally of the pin to receive the upper end of the wire 43. The arrangement is such that the wire extends through the slot in the bifurcated end of the lever 31 and is secured to the pin 51 as by set screw 52. With this construction, the pin is freely mounted for rotation in the end of the lever 31 and axial movement of the pin is prevented by the wire 43.

It will be observed that the switch may be actuated to on and off position manually by the projecting portion 26 of lever 24, or the switch may be actuated by depressing the projections 41 on pedal members 40. If it is desired to install the mechanism without the pedal arrangement, the tubular member and pedals are omitted and the aperture in hub 35 provided with a plug. Subsequently, the pedal arrangement may be conveniently added to the mechanism.

What I claim is:

1. The combination of a switch housing having an opening in one side thereof, a switch mounted in the housing, of mechanism for operating said switch, said mechanism comprising a closure member for the opening of the housing, a switch actuating element carried by said closure member, a tubular guide member secured to said closure member and extending therefrom, a pair of pedal members movably mounted in the outer end of said guide member, and motion transmitting means housed within said guide member and operatively connecting said pedal members with said switch actuating element, said element being operable upon movement of said pedals to shift said switch into on and off positions.

2. The combination of a switch housing having an opening in one side thereof, a switch mounted in the housing, of mechanism for operating said switch, said mechanism comprising a closure member for the opening in the housing, a switch actuating element mounted on said closure member, a tubular guide member secured to said closure member and extending therefrom, a pedal member movably mounted in the outer

end of said guide member, motion transmitting means arranged in said tubular guide member and operatively connecting said pedal and said switch actuating element, and means for detachably securing said closure member to the housing.

3. The combination of a switch housing having an opening in one side thereof, a switch mounted in the housing, of mechanism for operating said switch, said mechanism comprising a closure member for the opening in said housing, a rock shaft journalled in said closure member and being provided at its inner end with means engaging the operating handle of the switch, a lever secured to the outer end of said rock shaft, a tubular member detachably secured to the closure member and depending therefrom, a pair of foot pedals slidably mounted in said tubular member, and motion transmitting means operatively connecting said foot pedals with said lever, and means for detachably securing the closure member to the housing.

4. The combination of a switch housing having an opening in one side thereof, a switch mounted in the housing, of mechanism for operating said switch, said mechanism comprising a boxlike closure member with the bottom wall of said member acting as a closure for the opening in the housing, a switch actuating element journalled in the bottom wall of said member and being operable upon oscillation to actuate the switch into on and off positions, a tubular member arranged in one side wall of said end closure and extending outwardly therefrom, a foot pedal slidably mounted on said guide member, and motion transmitting means operatively connecting said pedal with the switch actuating element and being operable upon sliding movement of said pedal to effect oscillation of said actuating member, and means for detachably securing said closure member to the housing.

5. The combination of a switch housing having an opening in one side thereof, a switch mounted in the housing and mechanism for operating said switch, said mechanism comprising a boxlike closure member detachably secured to the body with the bottom wall of said member forming a closure for the opening in the body, a shaft pivotally mounted in the bottom wall of said member and being provided at its inner end with means operable to engage the actuating element of said switch, a lever secured to the outer end of said shaft, a tubular guide member detachably secured in one side wall of said closure member and depending therefrom, a pair of pedals movably mounted in said guide member, and motion transmitting means operatively connecting said pedals and said lever.
